UNITED STATES PATENT OFFICE.

WILLIAM L. HAYNES, OF CYNWYD, PENNSYLVANIA, ASSIGNOR TO WILLIAM SELLERS & COMPANY, INCORPORATED, OF PHILADELPHIA, PENNSYLVANIA, A CORPORATION OF PENNSYLVANIA.

GEARING.

982,603.

Specification of Letters Patent. Patented Jan. 24, 1911.

Application filed June 3, 1910. Serial No. 564,783.

To all whom it may concern:

Be it known that I, WILLIAM L. HAYNES, a citizen of the United States, residing at Cynwyd, county of Montgomery, and State of Pennsylvania, have invented a new and useful Improvement in Gearing, of which the following is a full, clear, and exact description, reference being had to the accompanying drawings, which form a part of this specification.

My invention relates to the same class of tools and is for substantially the same purpose as that described in Letters Patent No. 915,856, issued to me March 23rd, 1909.

Specifically, the invention relates to a construction, different from, and in some respects an improvement upon, the construction illustrated and described in the aforesaid patent, for the purpose of providing a rapid traverse movement in either direction, as well as the slow feeding motion, and to insure the disengagement or severance of the slow feeding motion while the rapid traverse movement is in operation, and to insure the engagement of the slow feeding motion except when positively held out of action.

I will first describe the embodiment of my invention illustrated in the accompanying drawings and then point out the invention in the claims.

In the drawings: Figure 1 is a side elevation of my device. Fig. 2 is a plan view, part of the rail being shown in section. Fig. 3 is a sectional plan view on the line 3—3 of Fig. 1. Figs. 4 and 5 are sections on the line 4—4 of Fig. 1, and clearly illustrates the operation of the various clutches embodied in my invention. Fig. 6 is a detail showing the means for shifting the positive clutch.

1 is a pulley carried at the top of one of the housings of the mill. 2 is a larger pulley carried at or near the bottom of the housing. The belt 120 connects these pulleys, passing under the pulley 3 and over the pulley 4 so that these pulleys are driven in opposite directions as indicated by the arrows. The pulley 3 is loosely mounted on the sleeve 5. The pulley 4 is loosely mounted on the sleeve 6. The sleeve 5 surrounds the shaft 7 and the sleeve 6 surrounds the shaft 8, both shafts being free to rotate in the respective sleeves.

Spined upon the shaft 7 is a clutch member 9, and spined upon the shaft 8 is a

clutch member 10. The other or corresponding clutch member in each case is carried respectively by the pulleys 3 and 4. When either clutch member 9 or 10 is engaged with its corresponding pulley, either 60 the shaft 7 or the shaft 8 will revolve, but, as before described, the shafts will revolve in opposite directions.

On the end of the shaft 7 is a pinion 11 and on the end of the shaft 8 is a pinion 12, 65 so that when these shafts revolve the pinions revolve. These two pinions engage with a wheel 13 mounted on the hub of a pinion 14. The pinion 14 is keyed to the feed screw or feed rod driving shaft 15. On the other end 70 of this shaft 15 is a clutch member 16 engaging with a spiral gear 17, which meshes with a corresponding spiral gear 18 carried upon the feed shaft 19. When the clutch surfaces 16 and 17 are engaged, the motion 75 of the feed shaft 19 will be transmitted through the spiral gears and the clutch 16 to the shaft 15, and, by appropriate mechanism, the rotation of shaft 15 is transmitted to the feed rod and the feed screw. 80

As may be seen, and as stated before, when the clutch surfaces 16 and 17 are engaged, the feed screw or feed rod is given a slow feeding movement from the feed shaft 19. If, however, the clutch surfaces 16 and 17 be 85 disengaged and either the clutch 9 or 10 engaged with its corresponding pulley, the shaft 15 will, dependent upon whether the clutch 9 or clutch 10 is in action, revolve in one direction or the other and at the speed 90 produced by the belt and pulleys, before described, by which the rapid traverse motion may be transmitted in either direction to the feed screw or feed rod.

The mechanism by which I move into action the desired clutch member 9 or 10, and simultaneously therewith disengage the clutch surfaces 16 and 17, is as follows: The clutch surfaces 16 and 17 are normally held in engagement with each other by the rods 44 and 45, provided with heads against which bear the springs 46 and 47. The other ends of these rods 44 and 45 are connected to the yoke 43, and the action of the springs is such that the yoke is drawn toward the spiral gear, and the clutch teeth brought into engagement so that the clutch surfaces 16 and 17 are normally connected. The clutch members 9 and 10 are connected to a frame 24 by, 105 respectively, the yokes 35 and 36. The frame 110

24 is mounted on the shaft 28. From opposite ends of this frame 24 extend the links 29 and 30. The link 30 is connected by the lever 31 and links 32, with the bell crank 33 and handle 34.

5 37 are levers connected to link 29 and having a jaw portion 38, one surrounding one pin 39 and the other the other pin 39 on the yoke 43. Corresponding levers 40 are 10 operatively connected with the lever 31.

10 When the handle 34 is moved in one direction, it will move the clutch 10 into engagement and positively separate the clutch members 16 and 17, compressing the springs 15 46 and 47. When the handle is again brought to the neutral position the clutch 10 is released and the springs return the clutch members 16 and 17 into engagement. When the handle 34 is moved in the other direction, the clutch member 9 is brought into engagement with its pulley and at the same time, through the medium of the frame 24 and the link 29, the levers 37 are acted upon to sever the connection between the clutch members 20 16 and 17, and which, as in the former case, compresses the springs 46 and 47. As may be seen, by this arrangement, through the medium of the pulley and belt, a fast traverse movement may be given. It also may 25 be seen that this movement may be given in either direction, and in whichever direction it be given the feeding clutch is out of action and the rapid traverse movement continues only so long as the feeding clutch mechanism is out of action. This arrangement, by 30 means of the belt and the appurtenant mechanism, is very valuable in that it affords a releasing element which will yield before a breaking load is brought on the rapid traverse mechanism.

35 Having now fully described my invention, what I claim and desire to protect by Letters Patent is:—

1. The combination with a driven member, a driving member, a clutch for engaging the said driving and driven members, said clutch being normally in engagement, of two pulleys revolving in opposite directions, means to connect either pulley with the 45 driven member and simultaneously disengage the clutch connection between said driven member and the driving member.

2. The combination with a driven member, a driving member, a clutch for engaging the 55 said driving and driven members, said clutch being normally in engagement, of two belt driven pulleys revolving in opposite directions, means to connect either pulley with the driven member and simultaneously disengage the clutch connection between said driven member and the driving member.

3. The combination with a driven member, a driving member, a clutch for engaging the 60 said driving and driven members, said clutch being normally in engagement, of two pul-

ley shafts, a pulley for each shaft, said pulleys being normally disconnected from their shafts, said pulleys revolving in opposite directions, connecting mechanism between said pulley shafts and the driven member, a clutch 70 for each pulley for engaging it with its shaft, connecting mechanism between said pulley clutches and driving member clutch, whereby either pulley may be engaged with its shaft and the driving clutch simultaneously released. 75

4. The combination with a driven member, a driving member, a clutch for engaging the said driving and driven members, said clutch being normally in engagement, of two pulleys, a belt passing around said pulleys in opposite directions, pulley shafts, pulleys normally disengaged from said shafts, connecting mechanism between said pulley shafts and the driven member, a clutch for 80 each pulley for engaging it with its shaft, connecting mechanism between said pulley clutches and driving member clutch, whereby either pulley may be engaged with its shaft and the driving clutch simultaneously released. 85

5. The combination with a driven member, a driving member, a clutch for engaging the said driving and driven members, said clutch being normally in engagement, of two pulley shafts, a pulley for each shaft, said pulleys being normally disconnected from their shafts, said pulleys revolving in opposite directions, connecting mechanism between said pulley shafts and the driven member, a 95 clutch for each pulley for engaging it with its shaft, a rocking frame, connecting mechanism between said pulley clutches and said rocking frame on opposite sides of the rocking point of said frame, and connections between said frame and the driving member 100 clutch. 105

6. The combination with a driven member, a driving member, a clutch for engaging the said driving and driven members, said clutch being normally in engagement, of two pulley shafts, a pulley for each shaft, said pulleys being normally disconnected from their shafts, said pulleys revolving in opposite directions, connecting mechanism between said pulley shafts and driven member, a clutch for each pulley for 110 engaging it with its shaft, a rocking frame, connecting mechanism between said pulley clutches and said rocking frame on opposite sides of the rocking point of said frame, operating mechanism for said rocking frame 115 on one side of the rocking point of said frame, direct connecting mechanism between said operating mechanism and said driving member clutch and connecting mechanism between said frame and the driving member clutch on the opposite side of the rocking point of the frame. 120

7. The combination with a driven mem- 130

ber, a driving member, a clutch for engaging the said driving and driven members, said clutch being normally in engagement, of two pulley shafts, a pulley for each shaft, said pulleys being normally disconnected from their shafts, said pulleys revolving in opposite directions, connections between said pulley shafts and driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, a collar for the driving member clutch, a pin for moving said collar longitudinally, a lever having a jaw portion around said pin, connecting mechanism between said lever and the operating mechanism, a second lever having a jaw portion around said pin, and connecting mechanism between said second lever and the rocking frame on the side of the rocking point of the frame opposite to that of the operating mechanism.

8. The combination with a driven member, a driving member, a clutch for engaging the said driven and driving members, said clutch being normally in engagement, of two pulley shafts, a pulley for each shaft, said pulleys being normally disconnected from their shafts, said pulleys revolving in opposite directions, connections between said pulley shafts and driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, a collar for the driving member clutch, two pins for moving said collar longitudinally, two sets of levers, said levers having a jaw portion, the jaw portion of one set of levers surrounding one pin, the jaw portion of the other set of levers surrounding the other pin, connecting mechanism between one lever of each set of levers and the operating mechanism, and connecting mechanism between the other lever of each set of levers and the rocking frame on the side of the rocking point of the frame opposite to that of the operating mechanism.

9. The combination with a driven member, a driving member, a clutch for engaging the said driven and driving members, said clutch being normally in engagement, of two pulley shafts, a pulley for each shaft, said pulleys being normally disconnected from their shafts, said pulleys revolving in opposite directions, connections between said pulley shafts and driven member, a clutch for each pulley for engaging it with its shaft, a rocking frame, connecting mecha-

nism between said pulley clutches and said rocking frame on opposite sides of the rocking point of said frame, operating mechanism for said rocking frame and connecting mechanism between said operating mechanism and said driving member clutch.

10. The combination with a driven member, a driving member, a clutch for engaging the said driven and driving members, said clutch being normally in engagement, of two pulley shafts, a belt driven pulley for each shaft, said pulleys being normally disconnected from their shafts, said pulleys revolving in opposite directions, connecting mechanism between said pulley shafts and driven member, a clutch for each pulley for engaging it with its shaft, a rocking frame, connecting mechanism between said pulley clutches and said rocking frame on opposite sides of the rocking point of said frame, and connections between said frame and the driving member clutch.

11. The combination with a driven member, a driving member, a clutch for engaging the said driven and driving members, said clutch being normally in engagement, of two pulley shafts, a belt driven pulley for each shaft, said pulleys being normally disconnected from their shafts, said pulleys revolving in opposite directions, connections between said pulley shafts and driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, direct connecting mechanism between said operating mechanism and said driving member clutch and connecting mechanism between said frame and the driving member clutch on the opposite side of the rocking point of the frame.

12. The combination with a driven member, a driving member, a clutch for engaging the said driven and driving members, said clutch being normally in engagement, of two pulley shafts, a belt driven pulley for each shaft, said pulleys being normally disconnected from their shafts, said pulleys revolving in opposite directions, connections between said pulley shafts and driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, a collar for the driving member clutch, a pin for moving said collar longitudinally, a lever having a jaw portion around said pin, connecting mechanism between said lever and the operating mechanism, a second lever having a

- jaw portion around said pin, and connecting mechanism between said second lever and the rocking frame on the side of the rocking point of the frame opposite to that of the operating mechanism.
13. The combination with a driven member, a driving member, a clutch for engaging the said driven and driving members, said clutch being normally in engagement, of two pulley shafts, a belt driven pulley for each shaft, said pulleys being normally disconnected from their shafts, said pulleys revolving in opposite directions, connections between said pulley shafts and driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, a collar for the driving member clutch, two pins for moving said collar longitudinally, two sets of levers, said levers having a jaw portion, the jaw portion of one set of levers surrounding one pin, the jaw portion of the other set of levers surrounding the other pin, connecting mechanism between one lever of each set of levers and the operating mechanism, and connecting mechanism between the other lever of each set of levers and the rocking frame on the side of the rocking point of the frame opposite to that of the operating mechanism.
14. The combination with a driven member, a driving member, a clutch for engaging the said driven and driving members, said clutch being normally in engagement, of two pulley shafts, a belt driven pulley for each shaft, said pulleys being normally disconnected from their shafts, said pulleys revolving in opposite directions, connecting mechanism between said pulley shafts and driven member, a clutch for each pulley for engaging it with its shaft, a rocking frame, connecting mechanism between said pulley clutches and said rocking frame on opposite sides of the rocking point of said frame, operating mechanism for said rocking frame and connecting mechanism between said operating mechanism and said driving member clutch.
15. The combination with a driven member, a driving member, a clutch for engaging the said driven and driving members, said clutch being normally in engagement, of two pulley shafts, two pulleys, a belt passing around said pulleys in opposite directions, said pulleys being normally disconnected from said pulley shafts, connections between said pulley shafts and driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, direct connecting mechanism between said operating mechanism and said driving member clutch and connecting mechanism between said frame and the driving member clutch on the opposite side of the rocking point of the frame.
16. The combination with a driven member, a driving member, a clutch for engaging the said driven and driving members, said clutch being normally in engagement, of two pulley shafts, two pulleys, a belt passing around said pulleys in opposite directions, said pulleys being normally disconnected from said pulley shafts, connections between said pulley shafts and driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, direct connecting mechanism between said operating mechanism and said driving member clutch and connecting mechanism between said frame and the driving member clutch on the opposite side of the rocking point of the frame.
17. The combination with a driven member, a driving member, a clutch for engaging the said driven and driving members, said clutch being normally in engagement, of two pulley shafts, two pulleys, a belt passing around said pulleys in opposite directions, said pulleys being normally disconnected from said pulley shafts, connections between said pulley shafts and said driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, a collar for the driving member clutch, a pin for moving said collar longitudinally, a lever having a jaw portion around said pin, connecting mechanism between said lever and the operating mechanism, a second lever having a jaw portion around said pin, and connecting mechanism between said second lever and the rocking frame on the side of the rocking point of the frame opposite to that of the operating mechanism.
18. The combination with a driven member, a driving member, a clutch for engaging the said driven and driving members, said clutch being normally in engagement, of two pulley shafts, two pulleys, a belt passing around said pulleys in opposite directions, said pulleys being normally disconnected from said pulley shafts, connections between said pulley shafts and said driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, direct connecting mechanism between said operating mechanism and said driving member clutch and connecting mechanism between said frame and the driving member clutch on the opposite side of the rocking point of the frame.

one side of the rocking point of said frame, a collar for the driving member clutch, two pins for moving said collar longitudinally, two sets of levers, said levers having a jaw portion, the jaw portion of one set of levers surrounding one pin, the jaw portion of the other set of levers surrounding the other pin, connecting mechanism between one lever of each set of levers and the operating mechanism, and connecting mechanism between the other lever of each set of levers and the rocking frame on the side of the rocking point of the frame opposite to that of the operating mechanism.

15 19. The combination with a driven member, a driving member, a clutch for engaging the said driven and driving members, said clutch being normally in engagement, of two pulley shafts, two pulleys, a belt passing around said pulleys in opposite directions, said pulleys being normally disconnected from said pulley shafts, connecting mechanism between said pulley shafts and said driven member, a clutch for each pulley for engaging it with its shaft, a rocking frame, connecting mechanism between said pulley clutches and said rocking frame on opposite sides of the rocking point of said frame, operating mechanism for said rocking frame and connecting mechanism between said operating mechanism and said driving member clutch.

20 20. The combination with a driven member, a driving member, a clutch for engaging the said driven and driving members, said clutch being normally in engagement, of two pulley shafts, a pulley for each shaft, said pulleys being normally disconnected from their shafts, said pulleys revolving in opposite directions, connections between said pulley shafts and said driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, a collar for the driving member clutch, a trunnioned yoke surrounding said collar, a lever having a jaw portion engaging said yoke trunnion, connecting mechanism between said lever and the operating mechanism, a second lever having a jaw portion engaging said yoke trunnion, and connecting mechanism between said second lever and the rocking frame on the side of the rocking point of the frame opposite to that of the operating mechanism.

25 21. The combination with a driven mem-

ber, a driving member, a clutch for engaging the said driven and driving members, said clutch being normally in engagement, of two pulley shafts, a belt driven pulley for each shaft, said pulleys being normally disconnected from their shafts, said pulleys revolving in opposite directions, connections between said pulley shafts and said driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, a collar for the driving member clutch, a trunnioned yoke surrounding said collar, a lever having a jaw portion engaging said yoke trunnion, connecting mechanism between said lever and the operating mechanism, a second lever having a jaw portion engaging said yoke trunnion, and connecting mechanism between said second lever and the rocking frame on the side of the rocking point of the frame opposite to that of the operating mechanism.

30 22. The combination with a driven member, a driving member, a clutch for engaging the said driven and driving members, said clutch being normally in engagement, of two pulley shafts, two pulleys, a belt passing around said pulleys in opposite directions, said pulleys being normally disconnected from said pulley shafts, connections between said pulley shafts and said driven member, a clutch for each pulley for engaging it with its shaft, a rocking frame, connecting mechanism between said pulley clutches and said rocking frame on opposite sides of the rocking point of said frame, operating mechanism for said rocking frame on one side of the rocking point of said frame, a collar for the driving member clutch, a trunnioned yoke surrounding said collar, a lever having a jaw portion engaging said yoke trunnion, connecting mechanism between said lever and the operating mechanism, a second lever having a jaw portion engaging said yoke trunnion, and connecting mechanism between said second lever and the rocking frame on the side of the rocking point of the frame opposite to that of the operating mechanism.

35 In testimony of which invention, I have hereunto set my hand, at Philadelphia, on this 1st day of June, 1910.

WILLIAM L. HAYNES.
